HUNTER'S BELT

Russell G. Moyer, 402 Deland Drive,
Utica, N.Y. 13502

Filed Feb. 10, 1972, Ser. No. 225,375

Term of patent 14 years

Int. Cl. D2—07

U.S. Cl. D2—381

FIG. 1 is a plan view of a hunter's belt showing my new design; and

FIG. 2 is a top edge view thereof.

I claim:

An ornamental design for a hunter's belt, as shown and described.
